CLAIM

The ornamental design for a nasal compression device, as
shown and described.

DESCRIPTION

FIG. 1 is a top view of a nasal compression device of our
design;

FIG. 2 is a bottom view thereof;

FIG. 3 is a rear view thereof;

FIG. 4 is a front view thereof;

FIG. 5 is a side view thereof;

FIG. 6 is a perspective view thereof in an open position; and,

FIG. 7 is a perspective view thereof in a compressed
position.
